DESIGN FOR AN UNDERGARMENT OR THE LIKE FOR WOMEN

Enid Bissett, New York, N. Y., assignor to Maiden
Form Brassiere Company, Inc., New York, N. Y., a corporation of New York

Application November 25, 1943, Serial No. 111,791

Term of patent 14 years

(Cl. D3—17)

To all whom it may concern:

Be it known that I, Enid Bissett, a citizen of the United States, residing at 965 Fifth Avenue, city of New York, county of New York, and State of New York, have invented a new, original, and ornamental Design for an Undergarment or the like for Women, of which the following is a specification, reference being had to the accompanying drawing, forming part thereof.

Fig. 1 is a front view of an undergarment, showing my new design; and
Fig. 2 is a side view thereof.

I claim:

The ornamental design for an undergarment or the like for women, as shown.

ENID BISSETT.
